[57] CLAIM

The ornamental design for a line trimmer cover with wheels, as shown and described.

DESCRIPTION

FIG. 1 is a front elevational view of the line trimmer cover with wheels showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a left side elevational view of the invention in use, the broken line showing of the line trimmer is for illustrative purposes only, and forms no part of the claimed design.

FIG. 1

FIG. 2

FIG. 3

FIG. 4

FIG. 5

FIG. 6

FIG. 7
